Specification for Design.

Patented June 7, 1921.

Application filed September 15, 1920. Serial No. 410,555. Term of patent 14 years.

To all whom it may concern:

Be it known that I, FRED S. CARVER, a citizen of the United States, and a resident of East Orange, county of Essex, and State of New Jersey, have invented a new, original, and ornamental Design for an Automobile Disk Wheel, of which the following is a specification, reference being had to the accompanying drawing, forming a part hereof.

Figure 1 of said drawing is a face view of an automobile disk wheel showing my new design.

Fig. 2 is a cross-sectional view taken on the line 2—2 of Fig. 1.

I claim:

The ornamental design for an automobile disk wheel, as shown.

FRED S. CARVER.
